CLAIM

The ornamental design for a paver square light, as shown and described.

DESCRIPTION

FIG. 1 is a top, front, left perspective view of a paver square light showing my design therefor;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The dotted lines indicate a boundary beyond which no claim is made for the design.

1 Claim, 5 Drawing Sheets(56)
